ATTORNEYS

UNITED STATES PATENT OFFICE.

ARTHUR H. KLINE, OF CHICAGO, ILLINOIS.

PLUG CONNECTION.

Application filed September 24, 1920, Serial No. 412,503. Renewed June 14, 1924.

To all whom it may concern:

Be it known that I, ARTHUR H. KLINE, a citizen of the United States, and a resident of the city of Chicago, in the county 5 of Cook and State of Illinois, have invented a new and useful Improvement in Plug Connections, of which the following is a full, clear, and exact description.

My invention relates to improvements in 10 plug connections, of the type in which the plug is provided with spring members arranged to engage the threads of the screw socket, so as to permit the plug to make instant connection, by thrusting it directly 15 into the socket, instead of screwing it in.

In connections of this type, it often happens that the plug is thrust into the socket, so as to effect an electrical connection, if the plug is held in a certain position, since 20 then the spring portions will enter the threads of the socket at the position where the contacts are effected, the same as they would be if the plug had been screwed up tight. When, however, the plug is rotated 25 about its axis, and then thrust in, it may not make contact in the ordinary device of this type, because it will not then be in the position corresponding to that when it is screwed into the socket as far as it will go.

30 An object of my invention is to provide a plug which will positively make connection when it is thrust into the socket, without necessitating the rotation of the plug about its axis to a particular position.

35 A further object of my invention is to provide a plug made up of threaded members of insulating material and having conducting members of relatively small area as compared with the insulating portion, thus 40 reducing the liability of short circuiting.

45 A further object of my invention is to provide a device of the type described, in which the electrical connections to the cable ends may be effected by removing the pivot pin, around which one of the insulating portions of the device oscillates.

50 Other objects and advantages will appear in the following specification, and the novel features of the invention will be particularly pointed out in the appended claim.

55 My invention is illustrated in the accompanying drawings, forming part of this application, in which

Figure 1 is a side view of the device,

Figure 2 is an end view,

Figure 3 is a view, showing the interior arrangement of the cable connectors, and

Figure 4 is a section along the line 4—4 of Figure 2.

In carrying out my invention, I provide 60 a body portion 1 which has hinged thereto at 2 a portion 3, the portions 1 and 3 constituting a cylindrical plug which is provided with threads 4. The portions 1 and 3 are made of insulating material. As will be seen 65 from Figure 4, the portion 3 is provided with a tongue 5 arranged to enter a recess 6 in the member 1, a pintle 7 being provided in the form of a screw, which passes through the tongue 5, the tongue pivoting 70 about the unthreaded portion of the screw. The body portion 1 has a central opening 8, through which a cable 9 is designed to pass. One strand of the cable is designed to be held by a screw 10 in electrical engagement with a metal plate 11, which is held by the screw to the insulating body portion. The plate 11 is provided with an extension 12, adapted to pass through an opening 75 13 in the body portion. The end of the extension 12 is bent upwardly and is fluted to conform with the threaded portion of the member 1, this threaded portion being disposed in a recess 14. The threaded portion lies normally flush with, or a little bit out- 80 side of the threaded portion of the member 1, so as to afford a good connection when the plug is inserted. The other strand of the cable is held by a screw 15, which also holds a metal plate 16 in place. 85 This plate 16 is bent in Z-shaped form (see Figure 4). A contact pin 17, which has a collar 18 (see Figure 4), is inserted in registering openings in the Z-shaped plate 16, and is normally pressed on by a spring 90 19, which tends to keep the pin 17 in an outer position. The Z-shaped metal portion 16 is adapted to enter between two integral guide portions 20, and these guide portions, in turn, are arranged to enter a recess 21 in 95 the pivoted portion 3. The latter has a recess 22 for the spring 23, which normally bears against the Z-shaped metal member 16 (as shown in Figure 4), so as to expand the plug, or, in other words, to keep the 100 threaded portion of the member 3 normally away from the threaded member 1.

From the foregoing description of the various parts of the device, the operation thereof may be readily understood. When 110

it is desired to make a quick connection with the ordinary threaded socket, all that is necessary is to insert the end of the plug in the outer end of the socket, and push it directly into the same. The end of the plug is beveled, as shown at 24, so as to permit it to enter the socket far enough to cause the closing of the hinged part toward the body portion 1 as the plug is being forced inwardly. The spring 23 keeps the parts in such position as to insure a good contact with the conducting plate 12. The central pin 17 will make a positive connection with the central contact 25 of the socket 26, even if the plug has retracted to adjust itself to the threads of the socket. There is, it will be observed, a spring pressed contact for both terminals of the socket.

The screw pin or pintle 7 may be withdrawn, and the member 3 removed to give access, at once, to the interior of the plug,

so as to secure the ends of the cable 9 to the conducting terminals. It will be observed that the tongue 5 prevents undue outward movement of the hinged member 3, but permits sufficient inward movement to enable the plug to be thrust directly into the socket.

I claim:

In an electrical connection, a body portion having a pair of lugs adjacent the outer end thereof, a V-shaped terminal plate disposed between said lugs, a movable contact pin provided with a shoulder slidably disposed in aligned openings of the side arms of said V-shaped terminal, and a spring disposed between said shoulder and the inner side arm of said V-shaped terminal, whereby the shoulder of said pin normally abuts against the outer side arm of said V-shaped member.

ARTHUR H. KLINE.
